COMBINATION COOLER AND ICE BOX

Whitney A. Haydel, Jeanerette, La., assignor of
one-sixth to Louis P. Bryant, Jeanerette, La.,
and one-sixth to Joe A. Daigre, New Iberia, La.

Application May 23, 1932. Serial No. 613,098

1 Claim. (Cl. 62—42)

This invention relates to a combination water cooler and ice box, the general object of the invention being to provide an insulated housing having a removable cover and provided with a partition for dividing the same into a lower ice receiving compartment and an upper food compartment with an opening connecting the parts together, a valve for closing the opening, and means for automatically opening the valve when the cover is in place, and automatically closing the valve when the cover is removed, thus preventing the warm air of the room contacting the cold air in the ice chamber when the cover is removed.

Another object of the invention is to provide a water cooling tank in the lower part of the ice chamber with means for connecting the chamber to a suitable source of supply so that cool water can be drawn from the tank whenever desired.

This invention also consists in certain other features of construction and in the combination and arrangement of the several parts to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:—

Figure 1 is a vertical sectional view through the invention.

Fig. 2 is a top plan view with the top removed.

Fig. 3 is a similar view with both the top and shelf removed.

Fig. 4 is a perspective view of the shelf.

Fig. 5 is a section on line 5—5 of Fig. 1.

Fig. 6 is a section on line 6—6 of Fig. 5.

Fig. 7 is a view of one of the baffle plates in the water tank.

Fig. 8 is the valve opening stem which is to be attached to the cover.

Fig. 9 is a fragmentary vertical sectional view through the housing with the cover in edge view and in raised position.

Fig. 10 is a section on line 10—10 of Fig. 9.

Fig. 11 is a fragmentary bottom plan view of the shelf showing the valve thereon.

Fig. 12 is a section on line 12—12 of Fig. 9.

In these drawings, the letter A indicates the box or housing and the letter B the cover thereof, both the cover and the housing being formed of inner and outer walls 1 and 2 with the space

between the walls filled with non-conducting material 3. A portion of the cover fits within the upper part of the housing and the cover is formed with a flange 4 which overlaps the top of the housing and a gasket 5 is placed between said flange and the upper edge of the housing.

A suitable lining 6 is also placed in the housing. A shelf or partition 7 resting on the support 8 divides the housing into a lower ice chamber 9 and an upper food chamber 10. The shelf 35 has an opening 11 therein which is normally held closed by a valve plate 12 guided by the rods 13 depending from the shelf and the springs 14 on the rods tend to hold the valve plate against the seat formed around the opening 11. A depending stem 16 attached to the under side of the cover will press the valve plate off its seat into open position when the cover is in position as shown in Fig. 1, so that the cold air from the ice chamber can pass into the food chamber and 70 when the cover is removed the springs 14 press the valve plate upon the valve seat around the opening 11 and thus prevents the cold air from being contacted by the warm air of the room in which the device is placed.

A flat narrow tank 16 is located in the bottom of the ice chamber and the ice rests thereon, and the combined drain and trap 17 passes through the bottom of the housing and through the tank with its upper end opening out into the ice 85 chamber to drain the water from the melting ice therefrom. The tank is provided with the V-shaped baffles 18 which have their ends spaced from the sides of the tank and are alternately arranged with the sloping baffles 19 which are 90 arranged in pairs with their inner ends spaced apart as shown in Fig. 5. A pipe 20 connects one end of the tank with a supply and an outlet pipe 21 is connected with the other end of the tank and has a part passing through the housing with 95 its outer end provided with a faucet 22.

Thus it will be seen from Fig. 5, that water enters one end of the tank and flows a tortuous path through the tank and escapes from the outlet pipe 21 when the valve 22 is opened. Thus 100 the water is quickly cooled.

Elongated rivets 23 connect the bottom and top of the tank together to reinforce the tank. Thus I have provided means which will keep food and the like at a low temperature and with the minimum amount of ice as the ice chamber is automatically closed by the valve 12 when the cover 1 is removed.

I also provide means for simply and quickly 110

cooling water for use for drinking purposes and the like.

It is thought from the foregoing description that the advantages and novel features of the 5 invention will be readily apparent.

It is to be understood changes may be made in the construction and in the combination and arrangement of the several parts provided that such changes fall within the scope of the ap- 10 pended claim.

Having thus described my invention, what I 15 claim as new is:—

A combined ice box and water cooler comprising a housing, a cover for closing the top of

the housing, a shelf extending horizontally across the housing and dividing the same into a lower ice chamber and an upper food chamber, said shelf having an opening therein, a spring pressed valve for normally closing the opening, a pro- jection on the cover for moving the valve to open position when the cover is in closed position, a tank in the bottom of the ice chamber, a water supply pipe connected with one end of the tank, an outlet pipe connected with the other end and having a valve at its outer end, baffles in the water tank for causing water passing there- 80 through to take a tortuous path.
